LIGHTING FIXTURE HAVING MEANS TO SHIELD THE LIGHT SOURCE

Edwin F. Guth, Florissant, Mo.

Application July 22, 1946, Serial No. 685,547

3 Claims. (Cl. 240—51.11)

1
This invention relates to lighting fixtures and more particularly to lighting fixtures which decrease glare.

Among the objects of the present invention may be noted the provision of lighting fixtures which shield the light source from the eyes of the observer; the provision of lighting fixtures which shield the light source from the eyes of the observer yet provide substantially unimpaired light upon the area to be illuminated; the provision of light fixtures which decrease indirect glare; the provision of lighting fixtures which have unusually low brightness characteristics combined with a high percentage of light output; and the provision of lighting fixtures which are rugged in construction, dependable in operation, efficient in action and which may be economically constructed. Other objects will be in part apparent and in part pointed out herein-after.

The invention accordingly comprises the elements and combinations of elements, features of construction, and arrangements of parts which will be exemplified in the structures hereinafter described, and the scope of the application of which will be indicated in the following claims.

In the accompanying drawings, in which one of various possible embodiments of the invention is illustrated,

Fig. 1 is a perspective view of one embodiment of the invention;

Fig. 2 is an enlarged transverse section of the Fig. 1 embodiment;

Fig. 3 is a bottom plan of the Fig. 1 embodiment; and

Fig. 4 is a view partially in section taken on line 4—4 on Fig. 3.

Similar reference characters indicate corresponding parts throughout the several views of the drawings.

Many lighting fixtures have either high brightness characteristics or a low light output while an ideal fixture would have low brightness characteristics without reducing light output. In general the lower the brightness characteristics the smaller will be the distance a person must move from a position directly under a lamp fixture to a position from which a direct view of the light source is impossible; that is, the smaller the observance angle and the less the glare.

It has been found in accordance with the present invention that a lighting fixture can be so designed as to have low brightness characteristics but with a percentage of light output equalling that of high glare or high transmis-

2
sion glass enclosed fixtures. This is accomplished by the use of a lamp fixture so constructed as to reduce the angle of direct light observance. This method of decreasing the brightness characteristics without reducing the percentage of light output shields the light source from normal and direct observation so as to protect the eyes of observer.

Referring now to the drawings, the lighting fixture 1 includes end plates 3, a case 5 and a baffle 7. A bracket 8 supports baffle 7 and socket mounting brackets 9 (see Fig. 2). The space between bracket 8 and case 5, bounded at each end by end plates 3, is utilized for mounting the customary electrical equipment indicated generally at 11. Socket mounting brackets 9 each carry lamp sockets 13, 15, 17 and 19 at each end.

A glass plate or panel 21 made from low absorption texture or configuration of crystal glass 20 is mounted in hinging hooks 23 and 25. A glass plate or panel 27, identical with glass plate 21 is mounted in hinging hooks 29 and 31. Hinging hooks 23 and 31 are supported respectively by channels 33 and 35 which are formed at the bottom edge of case 5. Hinging hooks 25 and 29 are respectively supported by U-shaped channels 36 and 37 which are mounted on baffle 7. It will be seen that glass plate 21 may be pivoted on flange 33 or channel 36 to permit access to the interior of the fixture without removing plate 21 from the fixture, or if preferred, glass plate 21 may thus be lifted out of the fixture. Similarly glass plate 27 may be pivoted on flange 35 or channel 37 to permit entry to the fixture, or may be lifted out of the fixture. Four fluorescent light tubes 39 are shown mounted in sockets 13, 15, 17 and 19. Baffle 7 extends down from the apex of the inverted V formed by plates 21 and 27 30° below a horizontal line from the center of the fluorescent tubes 39 mounted in sockets 13 and 19, that is, the depth of the inverted V.

From Fig. 1 it will be seen that the arrangement of the baffle 7 prevents direct observation of light from the fluorescent tubes 39 mounted in sockets 13 and 19 at an observance angle greater than that indicated respectively by line 41 and line 43. Flanges 33 and 35 similarly prevent observation of direct light from the fluorescent tubes 39 mounted in sockets 15 and 17 at an observance angle greater than that indicated respectively by line 45 and line 47.

Baffle 7 may be made of material which has light diffusing qualities or may be made of opaque material. The top section 48 of baffle 7, that is the portion above U-shaped channels

36 and 37, may be omitted if desired and baffle 7 attached to end plates 3. Interior surfaces 49 and 51 may be reflective throughout or translucent panels may be inserted in case 5. The angle at which diffusing glass plates 21 and 27 are mounted also aids in the reduction of glare, and these plates 21 and 27 prevent access of dirt into the fixture. Plates 21 and 27 may be made of transparent or translucent plastic instead of glass if desired. Other tubular lamps than fluorescent light tubes 39 may be used.

Attention is directed to my copending Patent 2,440,603 of April 27, 1948.

In view of the above, it will be seen that the several objects of the invention are achieved and other advantageous results attained.

As many changes could be made in the above construction without departing from the scope of the invention, it is intended that all matter contained in the above description or shown in the accompanying drawings shall be interpreted as illustrative and not in a limiting sense.

I claim:

1. A lighting fixture comprising an open-bottomed case, two light-transmitting panels carried by the case in position to provide a closure of inverted V-shape for its open bottom, a light source in the case above each panel, and a baffle extending downward from the apex of the closure for shielding the eyes of an observer from either light source throughout a range of angles of observance.

2. A lighting fixture comprising an elongate, open-bottomed case, two light-diffusing glass panels carried by the case in position to provide

a closure of inverted V-shape for its open bottom with the apex of the V extending longitudinally of the case, at least one tubular lamp extending longitudinally within the case above each panel, and a baffle extending downward from the apex of the closure and longitudinally for the length of the lamps for shielding the eyes of an observer from any lamp throughout a range of angles of observance.

3. A lighting fixture as set forth in claim 2, wherein the baffle extends downward sufficiently far to block direct light from any lamp with respect to an observer on one side of the fixture at observance angles above approximately 30° with the horizontal.

EDWIN F. GUTH.
